Primary Examiner — Karen E Kearney(74) *Attorney, Agent, or Firm* — Bacon & Thomas, PLLC(57) **CLAIM**

The ornamental design for a router, as shown and described.

DESCRIPTION

FIG. 1 is a perspective view of a router showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is another perspective view thereof.

The broken line illustration of a portion of the router in FIGS. 1, 4, 5 and 8 form no part of the claimed design.

1 Claim, 7 Drawing Sheets(56)
